UNITED STATES PATENT OFFICE

102,348

DESIGN FOR AN ILLUMINATED VANITY CASE OR THE LIKE

Ray A. Atherton, Oakland, Calif.

Application August 13, 1936, Serial No. 64,394

Term of patent 3½ years

To all whom it may concern:

Be it known that I, Ray A. Atherton, a citizen of the United States, residing at Oakland, in the county of Alameda and State of California, have invented a new, original, and ornamental Design for Illuminated Vanity Case or the like, of which the following is a specification, reference being had to the accompanying drawing, forming part thereof.

Fig. 1 is a perspective view of an illuminated vanity case, or the like in open position, showing my new design.

Fig. 2 is a perspective view of the illuminated vanity case, or the like in closed position.

Fig. 3 is a plan view of the insert member of the article illustrated in Figs. 1 and 2 showing the powder, rouge, and lamp receptacles and battery covers.

I claim:

The ornamental design for an illuminated vanity case or the like, as shown and described.

RAY A. ATHERTON.
